UNITED STATES PATENT OFFICE.

WILLIAM MOIR, OF CHICAGO, ILLINOIS.

TOY VEHICLE.

1,350,232.

Specification of Letters Patent. Patented Aug. 17, 1920.

Application filed December 30, 1919. Serial No. 348,285.

To all whom it may concern:

Be it known that I, WILLIAM MOIR, a citizen of the United States, residing at Chicago, in the county of Cook and State of Illinois, have invented new and useful Improvements in Toy Vehicles, of which the following is a specification.

This invention relates to toy vehicles and has for its object the provision of a novel 10 pedal operated drive mechanism therefor.

An important and more specific object is the provision of a drive mechanism including 15 pedal members connected by a lazy tongs construction with the crank shaft carrying the sprockets which transmits the motive power to the driving axle of the vehicle.

Another object is the provision of a device 20 of this character which will be simple and inexpensive in manufacture, easy to operate, which will be novel and attractive to a child, and which will be a general improvement in the art.

With the above and other objects and advantages in view, the invention consists in 25 the details of construction to be hereinafter more fully described and claimed, and illustrated in the accompanying drawings in which—

Figure 1 is a side elevation of a child's 30 vehicle formed to embody my invention,

Fig. 2 is a plan view,

Fig. 3 is an enlarged side elevation of my 35 drive mechanism,

Fig. 4 is a sectional view therethrough on the line 4—4 of Fig. 3.

Referring more particularly to the drawing, the letter A designates the body of the vehicle which may be formed to simulate an automobile or other type of vehicle attractive 40 to the eye of a child, and the letter B designates the dirigible or steering wheels. The letter C designates the rear axle which carries the driving wheels D.

In carrying out my invention I provide a 45 pair of plates 10, formed of metal, secured beneath the body A at the desired location between the front and rear wheels and each plate is provided with a longitudinal slot 11. Journalled through the plates 10 at one end

50 thereof, is a shaft 12 which has its ends provided with cranks 13 preferably extending in diametrically opposite directions. Associated with each plate is a lazy tongs construction including a plurality of links 14 pivotally connected at their ends and at their 55 points of crossing, as clearly shown. One

endmost link is pivotally connected, as shown at 15, with the adjacent plate 10. The end links at the other end are connected by the bolt 16 which rides within the adjacent slot 60 11, and pivotally connected with the bolt 16 is a pitman 17 connected with the adjacent crank 13. At the other end of the lazy tongs construction, that is at the end pivoted to the plate, the other endmost link is elongated 65 and angularly bent to provide a pedal 18 engageable by the foot of the operator. It will of course be understood that the construction is identically the same at both sides 70 of the vehicle except that the cranks 13 extend in opposite directions so that to operate the device it will be necessary to press the pedals 18 alternately.

In the operation of the device it will be seen that when an operator is seated within 75 a vehicle with his feet upon the pedals and presses the pedals alternately, the result will be the elongation and contraction of the lazy tongs construction at each side of the vehicle, the bolts 16 riding within the slots 11 and the pitman 17 transmitting the motion to the shaft 12. A suitable sprocket 19 is secured upon the shaft 12 and a chain 20 is trained about the sprockets 19 and the sprocket on the rear axle C whereby the motion will be 80 transmitted to the rear axle C and wheels D.

From the foregoing description and a 85 study of the drawings it will be apparent that I have thus provided a simple drive mechanism which will be unique and which will be particularly attractive to the eye of a child while being highly efficient in propelling the vehicle.

While I have shown and described the preferred embodiment of my invention, it is of 95 course to be understood that I reserve the right to make such changes in the form, construction, and arrangement of parts as will not depart from the spirit of the invention or the scope of the subjoined claims.

Having thus described my invention, I 100 claim:

1. In a toy vehicle including a body, front wheels therefor, a rear axle and wheels thereon, a drive mechanism comprising a pair of 105 plates secured beneath the body and having longitudinal slots, a crank shaft journalled through said plates and formed with crank portions, a chain and sprocket connection between said crank shaft and the rear axle, a 110 lazy tongs disposed against each plate and having one forward link pivoted thereon and

the other forward link provided with a pedal, means connecting the rear ends of each of the lazy tongs, said connecting means being slidable within said slot, and a pitman connected with said slidable connection and with the adjacent crank portion of the crank shaft.

2. In a toy vehicle including a body, front wheels therefor, a rear axle, and wheels carried thereby, drive mechanism comprising a pair of plates secured within said body and having longitudinal slots, a counter-shaft journaled through said plate, connecting means between said counter shaft and rear

axle whereby to impart rotary movement of the former to the latter, crank portions formed on said counter-shaft, a lazy tongs associated with each plate and having one forward link thereof pivoted upon the plate and the other forward link prolonged forwardly and terminating in a pedal, a bolt connecting the rearmost end links of each lazy tongs and slidable through the slot in the associated plate, and a pitman connected with each of said bolts and with the adjacent crank portion of the crank shaft.

In testimony whereof I affix my signature,
WILLIAM MOIR.
